United States Patent Office

Des. 221,782
Patented Sept. 7, 1971

221,782

ARMOIRE

Thomas Szirmay, Montreal, Quebec, Canada, assignor to Wentworth Industries, Montreal, Quebec Canada

Filed Apr. 14, 1969, Ser. No. 16,713

Claims priority, application Canada Oct. 15, 1968

Term of patent 7 years

Int. Cl. D6—04

U.S. Cl. D33—19

FIG. 3

FIG. 1 is a front elevation of an armoire showing the design;

FIG. 2 is a side elevation of FIG. 1; and
FIG. 3 is a top plan view of FIG. 1.

The side not shown in the drawing is a mirror image of FIG. 2, and the back of the armoire is conventionally flat.

I claim:

The ornamental design for an armoire, as shown and described.
